(57)

CLAIM

The ornamental design for a camera gimbal, as shown and described.

DESCRIPTION

FIG. 1 is a top front perspective view of a camera gimbal showing our new design;

FIG. 2 is a bottom rear perspective view of a camera gimbal showing our new design;

FIG. 3 is a front elevational view of the camera gimbal of FIG. 1;

FIG. 4 is a rear elevational view of the camera gimbal of FIG. 1;

FIG. 5 is a left side elevational view of the camera gimbal of FIG. 1;

FIG. 6 is a right side elevational view of the camera gimbal of FIG. 1;

FIG. 7 is a top plan view of the camera gimbal of FIG. 1; and,

FIG. 8 is a bottom plan view of the camera gimbal of FIG. 1.

(Continued)

The broken lines and all the areas within the solid line perimeter shown in FIGS. 1, 2, 5, and 6 depict portions of the camera gimbal that form no part of the claimed design.

1 Claim, 8 Drawing Sheets
